UNITED STATES PATENT OFFICE.

HARLEY D. WEED, OF GARVIN, MINNESOTA, ASSIGNOR OF TWELVE AND ONE-HALF PER CENT TO H. K. KVANBECK AND TWELVE AND ONE-HALF PER CENT TO JACOB KVANBECK, BOTH OF MINNEOTA, MINNESOTA, AND SEVEN AND ONE-HALF PER CENT TO ALFRED MATTSON AND SEVEN AND ONE-HALF PER CENT TO DAVID MATTSON, BOTH OF TAUNTON, MINNESOTA.

ROTARY MOTOR.

Application filed August 24, 1923, Serial No. 659,180. Renewed February 21, 1928.

This invention relates to a rotary motor, the general object of the invention being to provide means for passing the air compressed by the rotor through a carbureter 5 where it will pick up a certain amount of fuel and then leading it into a compression chamber which is provided with a valve controlled port where the gases resultant from the firing of the mixture in the said chamber 10 will enter the cylinder and act against the abutments to give the rotor its momentum.

Another object of the invention is to provide cam operated means for actuating the sliding abutment and the valve which controls the port leading from the compression chamber to the cylinder, such means acting to prevent binding of the abutments and valve.

A still further object of the invention is 20 to cause the moving parts to operate in a lubricant and to enclose the parts in a water jacket.

This invention also consists in certain other features of construction and in the 25 combination and arrangement of the several parts, to be hereinafter fully described, illustrated in the accompanying drawings and specifically pointed out in the appended claim.

30 In describing my invention in detail, reference will be had to the accompanying drawings wherein like characters denote like or corresponding parts throughout the several views, and in which:

35 Figure 1 is an elevation of the invention.

Figure 2 is a view of one end removed and the parts in section.

Figure 3 is a longitudinal sectional view.

40 Figure 4 is a section on line 4—4 of Figure 2.

Figure 5 is a plan view.

Figure 6 is a view of the rotor.

Figure 7 is a section on line 7—7 of Figure 6.

45 Figure 8 is a detail view of the sliding abutment and the cam engaging members thereon.

In these views 1 indicates a cylinder and 2 the rotor therein, 3 indicating the shaft to which the rotor is fastened. The cylinder is arranged in a casing 4 which forms an oil chamber and the shaft passes through the

ends of said casing. The interior of the rotor is in communication with said chamber so that when the chamber is filled with oil, said oil will circulate through the rotor. The casing is provided with an extension 4' in which is formed a combined compression and explosion chamber 5 which is in communication with the interior of the cylinder 60 by a port 6, compressed air being led into the chamber 5 by means of the pipe 7 which is connected with the port 8 which enters the cylinder immediately in rear of the sliding abutment 9, the port 6 being arranged in front of the abutment. A sliding valve 10 is arranged to control the port 6 and this sliding valve is made similar to the abutment. Each of these parts are arranged to slide in a chamber 11 and the stem 12 is engaged by a coil spring 13 which is adjustable by means of the set screw 14. A cross piece 15 is held against the upper edge of each member by a collar 16 and pins 17 are connected with the ends of each cross piece. 70 The lower ends of the pins of the abutment engage the cams 18 while the pins of the valve engage the cams 18'. The cams are arranged on the shaft 3 and are so arranged that the abutment 9 will be lifted just as soon as the piston 19 of the rotor starts to pass the port 8 and the cams will lift the valve 10 just as the explosion is taking place in the chamber 5 and the piston 19 has partly uncovered the port 6. A carbureter 20 is 85 connected with the pipe 7 so that the air passing through the pipes will be laden with gasoline or other fuel as it enters the chamber 5, a spark plug 21 being associated with the chamber 5 for exploding the charge. 90 Both abutments and the sliding valve are provided with packing means 22 for making gas tight connections and the rotor is provided with the packing rings 23. The packing means of the piston 19 are spring pressed 95 by means of the springs 24 and the pins 25. The combined inlet and exhaust port is shown at 26 and the extension 4' is provided with a water chamber 27 which is in communication with the water chamber for cooling the chamber 5 and the valve. The check valve for the chamber 5 is shown at 28.

From the foregoing it will be seen that the air previously drawn in through port 26 by

the suction created by the moving piston 19 will be compressed in the space ahead of the piston when said abutment passes the port 26 and said air will be led by the pipes 7 through the carbureter and into the chamber 5. As it passes through the carbureter it will be mixed with the vapors from the gasoline or other fuel therein so that when the mixture reaches the chamber 5 it will be of an explosive nature. The valve 10 will hold the mixture in a compressed state in said chamber. Just before the piston 19 reaches the sliding abutment 9, said abutment will be raised by the cams to permit the piston 19 to pass it and then it will drop back into engagement with the rotor. As soon as the piston 19 uncovers the port 6 the explosion will take place in the chamber 5 and the valve 10 raised to permit the gases to act on the piston 19 and abutment 9 and thus give the rotor its propelling stroke. When the piston 19 passes the port 26 the burnt gases will escape and air will be drawn in as the piston 19 moves upwardly.

25 The ends of the casing and the ends of the cylinder are removable so as to provide access to the parts.

It is thought from the foregoing description that the advantages and novel features 30 of my invention will be readily apparent.

I desire it to be understood that I may make changes in the construction and in the combination and arrangement of the several

parts, provided that such changes fall within the scope of the appended claim.

35

What I claim is:—

A rotary motor comprising a casing having an extension, a cylinder in the casing and a combustion chamber in the extension, a carbureter, means for connecting its outlet 40 to the combustion chamber, the cylinder having a pair of ports in its upper part, one of which connects the combustion chamber with the cylinder, means for connecting the other port with the inlet end of the carbureter, the lower part of the cylinder having a combined inlet and exhaust port therein, a rotor in the cylinder, a piston therein arranged to close the ports as it passes over the same, a sliding abutment in the casing and arranged 45 between the upper ports which are connected respectively with the carbureter and the combustion chamber, said abutment engaging the rotor, a sliding valve for controlling the port leading to the combustion chamber, cams connected with the rotor, means associated with the abutment and valve and operated by the cams for raising the abutment to permit the piston to pass the same and for lifting the valve as soon as the port leading 50 to the combustion chamber is partly uncovered by the piston and means for firing the charge in the combustion chamber just before the valve is opened.

In testimony whereof I affix my signature.

HARLEY D. WEED.
